(57) **CLAIM**

I claim the ornamental design for bullet jewelry, as shown and described.

DESCRIPTION

FIG. 1 is a top perspective view of the bullet jewelry design. FIG. 2 is a front elevation view of the bullet jewelry design. FIG. 3 is a top plan view of the bullet jewelry design; and, FIG. 4 is a bottom plan view of the bullet jewelry design. The broken lines shown in the drawings illustrate portions of the bullet jewelry and form no part of the claimed design.
